Filed Dec. 30, 1966, Ser. No. 606,209

9 Claims. (Cl. 81—15.7)

ABSTRACT OF THE DISCLOSURE

A tire repairing injector tool is provided in which a needle is utilized to inject the repair material into a tire, and means are provided for bowing a portion of the needle between axially-spaced needle-supporting fulcrum points, whereby to lock the needle against axial movement during the injection of the repair material.

This invention relates to injector tools of the type described in U.S. Patent No. 3,110,205, but has reference more particularly to improved means for locking the needle of the tool against axial movement or displacement during insertion of the puncture sealing material into the puncture in a tubeless vehicle tire and removal of the needle from the tire.

A primary object of the invention is to provide improved means for locking the needle, whereby the needle is locked at three axially spaced points, and is positively held against movement during insertion as well as removal of the needle in the tire.

Another object of the invention is to provide improved locking means of the character described, in the use of which an increase in the pushing or inserting force results in an increase in the effectiveness of the locking action.

A further object of the invention is to provide improved means of the character described, in the form of an easily manipulated wheel lock of simple and inexpensive construction, which can be quickly and easily assembled with the other parts of the tool.

A still further object of the invention is to provide a wheel lock of the character described, which can be quickly and easily released for the purpose of resetting or adjusting the effective length of the needle.

Other objects and advantages of my invention will be apparent during the course of the following description.

In the accompanying drawings forming a part of this specification, and in which like numerals are employed to designate like parts throughout the same,

FIG. 1 is a top plan view of an injector tool embodying the invention;

FIG. 2 is a fragmentary side elevational view of the forward portion of the tool;

FIG. 3 is a front elevational view of the tool;

FIG. 4 is a transverse cross-sectional view, taken on the line 4—4 of FIG. 1;

FIG. 5 is a fragmentary vertical cross-sectional view, taken on the line 5—5 of FIG. 3;

FIG. 6 is a fragmentary cross-sectional view, taken on the line 6—6 of FIG. 3, and

FIG. 7 is a bottom plan view of the locking wheel.

In a tool of the character described, it is essential that the needle, after being set to provide an effective portion thereof which is inserted in the puncture of the tire, be locked in said pre-set position, so that the needle can be inserted in the puncture without fear or danger of slipping relatively to the tool.

It is also essential that the needle be locked in said position, so that when it is withdrawn from the tire, it cannot slip relatively to its holder, so as to increase its effective length, since any undesirable increase in its ef-

2

fective length can cause the needle to damage or puncture the side of the tire which is opposite the puncture which is being repaired or filled.

Referring more particularly to the drawings, the tool 5 will be seen to comprise a tube or cylinder 1 which is adapted to contain a cartridge or roll 2 of puncture repair material, such, for example, as that disclosed in the aforesaid U.S. Patent 3,110,205 or in U.S. Patent 3,049,164. The rear end of the tube is closed, and the forward end 10 of the tube is flared as at 3 and externally threaded as at 4 for the attachment thereto of a closure cap 5.

The cap 5 has a central opening 6 through which extends an externally threaded tenon or stem 7 of a cylindrical needle holder 8 having a conical forward portion 9.

The needle holder 8 is secured with its base against the cap 5 by means of a nut 10, a lock washer 11 being interposed between the nut and the inner wall of the cap.

20 The holder 8 has axially-aligned spaced passageways 12 and 13 for the passage therethrough of a needle 14, which has a rear portion extending into the tube 1 and an eye 15 spaced forwardly of the holder. The holder 8 also has a passageway 16 therein spaced below and parallel with the axis of the passageways 12 and 13 for the passage therethrough of the puncture sealing material 2, the forward end of which is threaded through the eye 15 of the needle 14.

The holder 8, which is preferably made as an aluminum die casting, is cored to provide a recess 17, having vertical spaced side walls 18 and 19, a front wall 20, a rear wall 21, and a bottom 22. The bottom 22 is spaced somewhat below the needle 14. At their upper ends, the side walls 18 and 19 terminate in horizontal ledges 23, from which side walls 24 and 25 extend vertically, these side walls being spaced laterally to a greater extent than the side walls 18 and 19, for a purpose to be presently explained.

30 The recess 17 is designed to receive a wheel 26 having in its periphery a groove 27 of V-shaped cross-section. A portion of the wheel and the groove, at the bottom of the wheel, are removed to provide a flat 28, which is perpendicular to a radial line drawn from the axis of the wheel to the center of the flat. The wheel 26 is mounted for rotation on a shaft or pin 29, the ends of which are mounted in the holder 8, as best seen in FIG. 4.

40 The upper portion of the wheel 26 has rigidly secured thereto a thumb-piece 30 having a longitudinally curved thumb rest 31 in its upper surface, which is knurled. This thumb-piece may, if desired, be molded or formed integrally with the wheel 26. The thumb-piece 30, which is substantially wider than the wheel is accommodated in the space above the ledges 23 and between the vertical walls 24 and 25.

50 In FIG. 5, as well as in the other figures, the wheel 26 is shown in its non-locking position, in which the flat 28 is substantially parallel with the axis of the needle 14, a slight clearance of several thousandths of an inch being provided between the flat 28 and the surface of the needle to permit the needle to be moved longitudinally to expose any desired portion thereof, forwardly of the needle holder 8.

60 In order to lock the needle 14 in position after it has been thus moved, and to prevent axial movement of the needle relatively to the holder during insertion of the needle in the tire, the wheel is rotated in an anti-clockwise direction, as viewed in FIG. 5, to the position approximately indicated by the broken line position of the thumb-piece 30. This is accomplished while gripping the tube 1 with the fingers and pressing the thumb-piece forwardly

and downwardly with the thumb of the hand which is gripping the tube.

This causes the portion of the needle 14 between the walls 20 and 21 to be bowed slightly downwardly, to the position shown in broken lines in FIG. 5, the points A and B of the holder acting as fulcrum points for the bowing action. The extent of bowing is very slight, being shown somewhat exaggeratedly in FIG. 5. At the same time, the groove 27 in the wheel 26 exerts a wedging action on the upper surface of the needle, which wedging action coacts with the aforesaid bowing action to effectively lock the needle against axial movement relatively to the holder 8, permitting the needle to be inserted into the tire as well as removed from the tire without danger of slipping. This wedging action is enhanced by reason of the fact that the wheel 26 is made of a relatively soft metal, such as aluminum, and the needle is usually made of steel or a hard ferrous alloy.

It may be noted that since the pushing force on the needle during insertion is to the left, as viewed in FIG. 5, that as this pushing force is increased, portions of the wheel of progressively increasing radii come into contact with the needle, so that the locking action on the needle is, in effect, increased as the pushing action is increased, thereby virtually eliminating any possibility of the needle slipping.

After the needle has been withdrawn from the tire, the wheel is restored to the solid line position shown in FIG. 5, thereby quickly and easily releasing the needle for any desired adjustment or for removal from the tool. Since the needle is of a resilient nature, the bowed portion of the needle is restored to its original straight condition, and there is no permanent distortion of the needle.

The use of a relatively soft alloy for the wheel is also effective from the viewpoint that the wheel does not mar the surface of the needle, although even if the wheel were made of steel, the extent of marring of the needle would be negligible.

After repeated use of the tool, the groove in the wheel adjacent the area at which it makes contact with the needle may become slightly worn or flattened, but due to the construction and manner in which the wheel is assembled with the holder, the wheel may be quickly and easily replaced with a new wheel, if necessary.

It is thus seen that I have provided improved locking means for locking the needle, whereby the needle is locked at three axially spaced points, that is to say, the points A and B and the point of engagement of the wheel with the needle, thereby effectively locking the needle against movement in its holder during insertion as well as removal of the needle from the tire.

It is also seen that I have provided improved locking means in the use of which an increase in the pushing or inserting force on the needle results in an increase in the effectiveness or efficiency of the locking action.

It is further seen that I have provided improved locking means in the form of an easily manipulated wheel lock or locking wheel, of simple and inexpensive construction, which can be quickly and easily assembled with the other parts of the tool, and which can be quickly and easily released for the purpose of resetting or adjusting the effective length of the needle.

It is to be understood that the form of my invention, herewith shown and described, is to be taken as a pre-

ferred example of the same, and that various changes may be made in the shape, size and arrangement of parts thereof, without departing from the spirit of the invention or the scope of the subjoined claims.

We claim:

1. In a tool of the character described, a needle, a holder having a recess therein for passage of said needle, means for supporting a portion of said needle at points spaced axially of said needle, said portion of said needle being free to bow in response to pressure applied to said needle at a point intermediate said spaced points, and means for applying such pressure to said needle for locking said needle against axial movement relatively to said holder.

2. A tool, as defined in claim 1, wherein said pressure applying means has means for wedgingly engaging said portion of said needle.

3. A tool, as defined in claim 1, wherein said recess has a bottom spaced below said needle.

4. A tool, as defined in claim 3, wherein said recess has end walls between which said portion of said needle extends, said end walls providing fulcrum points for the support of said portion of said needle.

5. In a tool of the character described, a holder having a recess therein for passage of a needle, said holder having means for supporting said needle at points spaced axially of said needle, means for bowing the portion of said needle between said points for locking said needle against axial movement relatively to said holder, said bowing means engaging said needle at a point intermediate said spaced points, said bowing means comprising a wheel mounted for rotary movement in said holder.

6. A tool, as defined in claim 5, wherein said wheel has a V-shaped groove in its periphery, and the bottom of said wheel is provided with a flat which is perpendicular to a line drawn from the center of said wheel to the center of said flat.

7. A tool, as defined in claim 6, wherein said wheel is provided at a point substantially diametrically opposite from said flat with means for rotating said wheel.

8. A tool, as defined in claim 7, wherein said last-named means comprises a thumb piece adapted to be engaged by the thumb of the user of said tool.

9. In a tool of the character described, a holder having a recess therein for passage of a needle, means for supporting a portion of said needle at points spaced axially of the needle, said portion of said needle being free to bow in response to pressure applied to said needle at a point intermediate said spaced points, and means for applying such pressure to said needle, for locking said needle against axial movement relatively to said holder when said needle is inserted into a tire, said last-named means including means responsive to the pressure of said needle into said tire for increasing said locking action.
